(57) **CLAIM**

The ornamental design for a size marker, as shown and described.

DESCRIPTION

FIG. 1 is a perspective view of a size marker showing my new design; the broken lines being for illustrative purposes only and forming no part of the claimed design.

FIG. 2 is an enlarged perspective view of the size marker of FIG. 1, shown at a slight rotation of the viewpoint toward the vertical and to the right.

FIG. 3 is a top plan view of the size marker.

FIG. 4 is a front side elevation view of the size marker.

FIG. 5 is a side elevation view of the size marker rotated 90 degrees to the left from the side of FIG. 4; the side view opposite the side shown in this figure being the same.

FIG. 6 is a side elevation view of the size marker on the side directly opposite the side of FIG. 4; and of the side directly opposite the side of FIG. 5; and,

FIG. 7 is a bottom plan view of the size marker.
